UNITED STATES PATENT OFFICE.

GUNNAR EMANUEL EHRLING, OF CHICAGO, ILLINOIS, ASSIGNOR TO BATES VALVE
BAG COMPANY, OF CHICAGO, ILLINOIS, A CORPORATION OF WEST VIRGINIA.

WIRE-TWISTING MACHINE.

1,199,771.

Specification of Letters Patent.

Patented Oct. 3, 1916.

Application filed July 1, 1915. Serial No. 37,428.

To all whom it may concern:

Be it known that I, GUNNAR EMANUEL EHRLING, a citizen of the United States, residing at Chicago, in the county of Cook and State of Illinois, have invented a certain new and useful Improvement in Wire-Twisting Machines, of which the following is a specification.

My invention relates to improvements in wire twisting means, and has for some of its objects to provide a new and improved means for twisting a wire tie about the neck of a bag or other package; to provide means for lubricating such twisting means; to minimize the wear on the twisting means, and to inclose all the working parts in an oil casing.

The invention is illustrated more or less diagrammatically in the accompanying drawings, wherein—

Figure 1 is a plan view of a bench tool with cover removed; Fig. 2 is a section on the line 2—2 of Fig. 1 with cover in place; Fig. 3 is a longitudinal section through a modified form showing my invention applied to a hand tool; Fig. 4 is a section on the line 4—4 of Fig. 3.

Like parts are indicated by like letters throughout the several figures.

Referring first to the bench tool shown in Figs. 1 and 2, a long rectangular box A is divided by a transverse partition A¹ into a spring chamber A² and twisting chamber A³. The rod A⁴ passes through the partition A¹ and the end wall A⁵ of the box, said end wall being provided with a stuffing box A⁶.

A⁷ is a twisting head on the outer end of the rod and from it project outwardly the twisting spring fingers A⁸ having hooks A⁹ in their ends to engage the tie A¹⁰ which is to be twisted about the neck of the bag A¹¹.

B is a short worm or helical gear rigidly mounted on the rod A⁴ and in mesh with a long rack B¹ in the chamber A³. This rack is located beneath the rod though in mesh with the gear so that a longitudinal movement of the rod will cause its rotation by virtue of the interlocking of the rack and worm.

B² is a spring coil about the rod or shaft A⁴ adapted to be compressed between the partition wall A¹ and the head B³ on the end of the shaft.

B⁴ is a cover adapted to close both the

chambers A² and A³ and removably held in position by screws B⁵.

In order to provide means for adjusting the twist given to the wire, it is only necessary to limit the longitudinal movement of the rod because the number of twists bear direct relation to the distance the rod is moved. In order to provide for this the inside wall of the chamber A³ is provided in the preferred form with three notches, C, C¹, C² and in one of these notches is located a stop plate C⁴ notched as indicated to pass over and straddle the rod and project down providing a stop against which the gear B may impinge. It will be understood that this stop is held in place by the cover and when that is removed the stop plate may be withdrawn or placed in any one of the notches at the will of the operator. The lugs C⁵ are provided so that the box may be bolted or otherwise fastened to a work bench or table.

In the hand form shown in Figs. 3 and 4, the hollow handle D is provided at its smaller end with a bearing sleeve D¹ and stuffing box D²; for the rod D³, the rod having on the end the wire twisting means D⁴. Access to the interior of the hollow handle is obtained by means of the screw-threaded plug E and in this hollow interior is located a short worm or helical gear E¹ on the inner end of the rod D³. This gear is in mesh with a long rack E² held in position on the handle by the screws E³. The rack is shown as semi-circular in cross section so as to make it conform with the interior of the handle. No spring is here provided.

It will be understood that the rod D³ is stiff, and the bearing D¹ guides and holds it in position; and it is this stiffness of the rod and this tubular bearing D¹ which combine to hold the gear E¹ in mesh with the rack E². This combination is possible only of course owing to the shortness and relative rigidity and heaviness of the rod.

Of course it will be understood that I do not wish to be limited to the precise forms, structures and arrangements shown, as they may be greatly varied without departing from the spirit of my invention.

I have shown my apparatus as applied to hand operated devices, but of course my invention is equally applicable to power operated structures.

I have shown two projecting arms with hooks on the end, but any device suitable for engaging or holding any kind of tie could be used with my invention. These arms in some instances are spring arms, but they need not be.

The use and operation of my invention are as follows:—Referring first to the bench tool the box is bolted in position. The two chambers are filled with oil and the adjustable stop is put in the desired position depending on the number of turns to be given. The cover is placed in position covering and closing the two oil chambers. The operator, introducing the neck of the bag between the two spring fingers, drops the tie into the hook and pulls on the bag. The tie is drawn out permitting the bag to pass out from between the fingers into the position shown in Fig. 2. Further pulling results in a longitudinal displacement of the rod and associated parts and this results in a rotation of the rod twisting the tie about the neck of the bag. The operator then having finished the twisting movement releases the wire from the hook and the spring withdraws the rod returning the parts to their previous positions. The stuffing box prevents discharge of the lubricant and the smooth rod being guided by the bearing or bearings and protected by the stuffing box is kept smooth and clean and no foreign substance permitted to enter the working chamber.

In the hand form the bag will be fixedly held. The operator will pass the tie around the bag and engage its end with the hook and then pull on the handle. Since he holds the handle it does not rotate, the rod does and the tie is twisted. The lubricant which may be contained within the handle lubricates the gear and rack and thus prevents all undue abrasion or cutting.

It will be understood that the two-part rod rotating means are the rack B^1 and the helical gear B which are in mesh one with another, and these two parts together cooperate or interact to rotate the rod.

I claim:

1. A wire twisting device comprising a longitudinally movable rod, wire engaging means carried thereby, a short helical gear thereon, a long rack in mesh with the gear, and a support for the rod and rack to hold them in operative relation.

2. A wire twisting device comprising a longitudinally movable rod, wire engaging means carried thereby, a short helical gear thereon, a long rack in mesh with the gear, and a housing for the gear and rack to hold them in operative relation.

3. A wire twisting device comprising a longitudinally movable rod, wire engaging means carried thereby, a helical gear thereon, a rack in mesh with the gear, and an

oil-retaining housing for the gear and rack to hold them in operative relation.

4. A wire twisting device comprising a longitudinally movable rod, wire engaging means carried thereby, a helical gear thereon, a rack in mesh with the gear, and a support for the gear and rack to hold them in operative relation, the rod being in contact with the support at a point removed from the helical gear. 75

5. A wire twisting device comprising a longitudinally movable rod, wire engaging means carried thereby, a helical gear thereon, a rack in mesh with the gear, and an oil-retaining housing for the rod and rack to hold them in operative relation, the gear being supported by the housing at a point removed from the helical gear. 80

6. A wire-twisting device comprising a longitudinally movable rod, wire-engaging means carried thereby, a short helical gear thereon, a long rack in mesh with the gear, and a support for the rod, gear and rack to hold them in operative relation, the rod being in contact with and supported by the support at a point removed from the helical gear. 85

7. A wire twisting device comprising a longitudinally movable rod, wire engaging means carried thereby, a helical gear thereon, a rack in mesh with the gear, and an oil-retaining housing for the gear and rack to hold them in operative relation, the rod being circular in cross-section where it projects from the housing. 90

8. A wire twisting device comprising a longitudinally movable rod, wire engaging means carried thereby, a helical gear thereon, a rack in mesh with the gear, and a support for the rod and rack to hold them in operative relation, the rod being in contact with the support at a point removed from the helical gear, the rod being circular in cross-section where it projects from the housing. 100

9. A wire twisting device comprising a longitudinally movable rod, wire engaging means carried thereby, a helical gear thereon, a rack in mesh with the gear, and an oil-retaining housing for the gear and rack to hold them in operative relation, the rod being circular in cross section where it projects from the housing and provided with a stuffing box to surround it at that point. 110

10. A wire twisting device comprising a longitudinally movable rod, wire engaging means carried thereby, a helical gear thereon, a rack in mesh with the gear, and a support for the gear and rack to hold them in operative relation, the rod being in contact with the support at a point removed from the helical gear, the rod being circular in cross section where it projects from the housing and provided with a stuffing box to surround it at that point. 120
